ALTERNATING OR VARYING PRESSURE-
ACTUATED PUMP

Louis Nikas, Jr., and Louis Nikas, Sr., Bronx, N. Y., assignors, by direct and mesne assignments, of thirty-seven and one-half per cent to said Louis Nikas, Jr. and sixty-two and one-half per cent to said Louis Nikas, Sr.

Application December 16, 1937, Serial No. 180,100

10 Claims. (Cl. 103—4)

This invention relates to new and useful improvements in air and liquid, suction and pressure pumps.

The invention proposes an alternating or varying pressure actuated pump designed in such a manner that it can be connected directly and unobstructedly (by slide or control devices) to an alternating or varying pressure producing source, and so that it will operate in synchronization with said source. It is contemplated that the source may be obtained from an engine cylinder, or compressor cylinder, or air pump or liquid pump cylinders.

More specifically, the invention contemplates an arrangement of parts in such a manner that the pressure moves a piston or pistons in one direction, and during that movement that pressure is applied to the liquid, by a liquid pump, suction action is applied to the air indirectly by building tension in a spring or springs, and said springs act to return the piston to the neutral position. It is proposed that during the return motion suction be applied to the liquid and pressure be applied to the air, by an air pump, and then the operation repeated.

The invention has for an object the construction of a device as mentioned which is characterized by an air cylinder having an air inlet and outlet, each controlled by one way valves, a piston for the cylinder, and means for oscillating the piston to pump air from the inlet to the outlet.

The invention contemplates associating a stem slidably longitudinally on said piston and to provide said stem with a head engaging in a hollow in the piston and arranged so that the piston moves the stem in one direction only.

Further, the invention contemplates the provision of resilient means for urging the stem in the other direction and a fluid pump controlled in a specific manner by said stem.

The invention contemplates an arrangement by which the air pump may be continuously actuated from an alternating or varying vacuum or pressure supply such as is present on an engine, and it is proposed to associate a liquid pump with the air pump in a manner so that there is a constant liquid and air pressure.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a vertical sectional view of a device constructed according to this invention.

Fig. 2 is a horizontal sectional view taken on the line 2—2 of Fig. 1.

Fig. 3 is a horizontal sectional view taken on the line 3—3 of Fig. 1.

Fig. 4 is a fragmentary vertical sectional view taken on the line 4—4 of Fig. 1.

Fig. 5 is a fragmentary view similar to a portion of Fig. 1, but illustrating a modification of the invention.

Fig. 6 is a similar view to Fig. 5, illustrating a still further modified form of the invention.

The alternating air actuated liquid and air pump, according to this invention, comprises an air cylinder 10 having an air inlet 11 and an air outlet 12. A one way valve 13 controls the inlet 11. A one way valve 14 controls the outlet 12. A piston 13' is slidably mounted within the cylinder 10.

A means is provided for oscillating the piston 13' to pump air from the inlet to the outlet. This means includes an auxiliary piston 13^a connected 25 with the piston 13' and arranged on one side thereof and operating in an auxiliary cylinder 15. This auxiliary cylinder has an inlet 16 for alternating pressure as may be obtained from an internal combustion engine.

The piston 13' is resiliently supported in a manner so as to float in a neutral position. From this position it may be moved in one direction and then in the other. The means for floating the piston 13' includes a disc 17 which is stationarily 35 mounted spaced from the piston 13'. This disc has a projecting flange 17^a. An expansion spring 18 is interposed between the piston 13' and one side of the flange 17^a. Another spring 19 is interposed between the other side of the flange 17^a 40 and a collar 20. This collar 20 is mounted on a bushing 21 which is fixedly mounted upon the piston 13'.

A stem 22 is slidably supported longitudinally on the piston 13' and has a head 22^a engaging 45 within a hollow 23 in the piston 13'. The parts are so arranged that the piston 13' when moving in one direction may move the stem 22 along with it in this direction, but when moving in the other direction it does not affect the position 50 of the stem 22.

A means is provided for urging the stem 22 in the direction opposite to that in which the stem 22 is moved by the piston 13'. This means includes a cup-shaped member 25 threadedly en- 55

gaged on the stem 22 and held in a fixed position thereon by an adjustable nut 26 for adjusting the fluid pressure. An expansion spring 27' acts between the cup-shaped member 25 and the disc 17 for urging the stem 22 as specified. Specifically, the stem 22 is urged upwards as viewed in Fig. 1. When the piston 13' moves downwards the bottom end of the bushing 21 will strike the head 22^a and so move the stem downwards. When the piston 13' moves upwards the hollow 23 will provide a place for the head 22^a to remain in without being moved by the piston.

The stem 22 is supported on a diaphragm 27 and is held fixedly thereon by nuts 28. The diaphragm 27 closes one end of a fluid chamber 29. This fluid chamber has an inlet 30 and a fluid outlet 31. A one way valve 32 controls the inlet 30. A one way valve 33 controls the outlet 31. The stem 22 is connected with the diaphragm 27 in a manner so that when the piston 13' moves the stem downwards, fluid is drawn into the fluid chamber 29. Thereafter, the resilient means 27' exerts a pressure on this fluid to force it out from the fluid outlet 31.

The air cylinder 10 comprises a short length of tubing 10^a arranged within an outer tube 10^b. The disc 17 rests upon one end of the tube 10^b. An auxiliary tube 10^c is also disposed within the outer tube 10^b and rests against the other face 30 of the disc 17. It is these tubes 10^a and 10^c which support the disc 17. The auxiliary cylinder 15 is formed in a cap 15^a which is threadedly engaged on the bottom end of the outer tube 10^b. This cap 15^a has a shoulder portion 15^b which forms a perch for the tube 10^a to firmly hold the tube in position. The fluid chamber 29 is formed by a top cap 29^a. This top cap also has a shoulder 29^b which forms an abutment for the edge portion of the diaphragm 27, and for a diaphragm holding ring 32 which is clamped and held in position by the edge portion of the cylinder 10^c.

The one way valve 14 includes a valve seat 14^a against which a valve ball 14^b is urged by a spring 14^c. A bushing 14^d is threadedly engaged in an opening in the cap 15^a and has a central opening for the passage of air and serves as a support for the spring 14^c. The valve 13 has a valve seat 13^a. A ball 13^b is adapted to engage the valve seat to close the valve. A spring 13^c acts against a portion of the cap 15^a and the valve ball 13^b to urge the valve closed. A bushing 13^d is threadedly engaged in an opening in the cap 15^a and is formed with a central passage through which the air may pass. The valve seat 13^a is formed upon the inner end of the bushing 13^d.

The valve 13 acts to permit air to be drawn into the air cylinder 10 when the piston 13' moves upwards and acts to prevent this air from being forced out from the air cylinder when the piston 13' moves downwards. The valve 14 acts to open and allow the air from within the air cylinder 10 to move outwards when the piston moves downwards, and this valve closes when the piston 13' moves upwards so that it is possible to draw in air through the open valve 13. The auxiliary piston 13^e is provided with several piston rings 36. The piston 13' also has piston rings 37.

The disk 17 has an annular recess 17^b which forms a seat for the bottom end of the spring 27'. The collar 28 is held upon the end of the bushing 21 by a locking element 38. The inlet valve 32 has a valve seat 32^a upon which a valve head 32^b is adapted to engage. A spring 32^c acts against the valve head to urge it upon its

seat. A bushing 32^d threadedly engages in the cap 29^a and is formed with a passage constituting the liquid inlet 30. The valve seat 32 is arranged upon the inner end of the bushing 32^d. The valve 33 engages against a valve 37 and includes a seat 33^a, a valve head 33^b engageable upon the seat, a spring 33^c urging the valve closed, and a bushing 33^d formed with a passage 31 for the liquid and forming an abutment for the spring 33^c to act against.

When the stem 22 is moved downward liquid will be drawn in through the inlet 30 since the valve 32 will open to permit this. Simultaneously, the valve 33 will close so that the fluid enters the fluid chamber 29. When the stem 22 completes its downstroke the spring 27' will supply an upward pressure to the stem 22 which in turn presses the diaphragm 27 against the liquid in the fluid chamber 29. The liquid under pressure will cause the valve 32 to close and cause the valve 33 to open and so the pressure of the liquid will be extended through the outlet 31. This is particularly desirable for supplying the fuel to a carburetor since there will be a constant feed of the fuel.

In Fig. 5 a modification of the invention has been disclosed which distinguishes from the prior form in the fact that there is an arrangement for adjusting the constant pressure of the liquid. This adjustment includes an annular member 40 which is threadedly engaged in an annular recess formed in the disc 17. This annular member 40 has a spring seat 47^b for the lower end of the spring 27. The annular member 40' has several handles 41 by which it may readily be gripped and turned. The arrangement is such that the annular member 40 may be screwed in or out to adjust the normal pressure of the spring 27. This indirectly affects the pressure of the liquid.

In Fig. 6, another modification of the invention has been disclosed. In this arrangement the inner ends of springs 18 and 19 engage the collar 20' of bushing 21' and the outer ends of springs 18 and 19 engage discs 17^e and 17^f, respectively, to keep the piston 13' in its normal position. The spring 27^e in this form of the invention engages disc 17^f at one end and a cup-shaped member 25' at the other end. The discs 17^e and 17^f are spaced by tubes 10^d, 10^e and 10^f of different lengths. These spacers may be interchanged to change the action of springs 18, 19 and 27^e.

In other respects this form of the invention is similar to the form previously illustrated and the same parts may be recognized by corresponding reference numerals.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:—

1. In an alternating or varying pressure or vacuum actuated pump, an air pump, an air cylinder having an air inlet and an air outlet, one way valves controlling said inlet and outlet, a piston in said cylinder, means for oscillating said piston to pump air from the inlet to the outlet, a stem slidably supported longitudinally on said piston and having a head engaging in a hollow in the piston arranged so that the piston moves

the stem in one direction only, resilient means urging the stem in the other direction, a fluid chamber having a fluid inlet and a fluid outlet, one way valves controlling said fluid inlet and fluid outlet, a diaphragm in said fluid chamber, and said stem being connected with said diaphragm, so that when the piston moves the stem, fluid is drawn into the fluid chamber and then the resilient means exerts a pressure on the fluid to force it out of the fluid outlet.

2. In an alternating or varying pressure or vacuum actuated pump, an air pump, an air cylinder having an air inlet and an air outlet, one way valves controlling said inlet and outlet, a piston in said cylinder, means for oscillating said piston to pump air from the inlet to the outlet, a stem slidably supported longitudinally on said piston and having a head engaging in a hollow in the piston arranged so that the piston moves 15 the stem in one direction only, resilient means urging the stem in the other direction, a fluid chamber having a fluid inlet and a fluid outlet, one way valves controlling said fluid inlet and fluid outlet, a diaphragm in said fluid chamber, 20 and said stem being connected with said diaphragm, so that when the piston moves the stem, fluid is drawn into the fluid chamber and then the resilient means exerts a pressure on the fluid to force it out of the fluid outlet, said means for 25 oscillating the piston comprising an auxiliary piston connected with said piston and working in an auxiliary cylinder provided with an inlet for a 30 fluctuating pressure or vacuum.

3. In an alternating or varying pressure or
35 vacuum actuated pump, an air pump, an air cylinder having an air inlet and an air outlet, one way valves controlling said inlet and outlet, a piston in said cylinder, means for oscillating said piston to pump air from the inlet to the outlet, a stem slidably supported longitudinally on said piston and having a head engaging in a hollow in the piston arranged so that the piston moves the stem in one direction only, resilient means urging the stem in the other direction, a
40 fluid chamber having a fluid inlet and a fluid outlet, one way valves controlling said fluid inlet and fluid outlet, a diaphragm in said fluid chamber, and said stem being connected with said diaphragm, so that when the piston moves the stem, fluid is drawn into the fluid chamber and then
45 the resilient means exerts a pressure on the fluid to force it out of the fluid outlet, a bushing being mounted upon said piston, and the head of said stem engaging the bottom of the bushing when
50 the piston moves downwards.

56 the piston moves downwards.

4. In an alternating or varying pressure or vacuum actuated pump, an air pump, an air cylinder having an air inlet and an air outlet, one way valves controlling said inlet and outlet, 60 a piston in said cylinder, means for oscillating said piston to pump air from the inlet to the outlet, a stem slidably supported longitudinally on said piston and having a head engaging in a hollow in the piston arranged so that the piston moves the 65 stem in one direction only, resilient means urging the stem in the other direction, a fluid chamber having a fluid inlet and a fluid outlet, one way valves controlling said fluid inlet and fluid outlet, a diaphragm in said fluid chamber, and said 70 stem being connected with said diaphragm so that when the piston moves the stem, fluid is drawn into the fluid chamber and then the resilient means exerts a pressure on the fluid to force it out of the fluid outlet, said resilient means for 75 urging the stem in the other direction comprising

a cup-shaped member fixedly mounted on the stem, a disc fixedly mounted on a portion of said cylinder and a spring engaging said cup-shaped member and said disc.

5. In an alternating or varying pressure or 5
vacuum actuated pump, an air pump, an air cylinder having an air inlet and an air outlet, one way valves controlling said inlet and outlet, a piston in said cylinder, mean for oscillating said piston to pump air from the inlet to the outlet, 10 a stem slidably supported longitudinally on said piston and having a head engaging in a hollow in the piston arranged so that the piston moves the stem in one direction only, resilient means urging the stem in the other direction, a fluid 15 chamber having a fluid inlet and a fluid outlet, one way valves controlling said fluid inlet and fluid outlet, a diaphragm in said fluid chamber, and said stem being connected with said diaphragm so that when the piston moves the stem 20 fluid is drawn into the fluid chamber and then the resilient means exerts a pressure on the fluid to force it out of the fluid outlet, said air cylinder comprising a tube mounted within an outer tube, said fluid chamber comprising another tube 25 mounted within the outer tube, and cap members mounted on the outer ends of the outer tube for forming the head ends of said cylinders. 30

6. In an alternating or varying pressure or vacuum actuated pump, an air pump, an air cylinder having an air inlet and an air outlet, one way valves controlling said inlet and outlet, a piston in said cylinder, means for oscillating said piston to pump air from the inlet to the outlet, a stem slidably supported longitudinally on said piston and having a head engaging in a hollow in the piston arranged so that the piston moves the stem in one direction only, resilient means urging the stem in the other direction, a fluid chamber having a fluid inlet and a fluid outlet, one way valves controlling said fluid inlet and fluid outlet, a diaphragm in said fluid chamber, and said stem being connected with said diaphragm so that when the piston moves the stem, fluid is drawn into the fluid chamber and then the resilient means exerts a pressure on the fluid to force it out of the fluid outlet, said air cylinder comprising a tube mounted within an outer tube, said fluid chamber comprising another tube mounted within the outer tube, and cap members mounted on the outer ends of the outer tube for forming the head ends of said cylinders, a disc being clamped in between the inner ends of said inner tubes, and resilient means acting against said disc and directly and indirectly against said piston for floating the piston.

inder comprising a tube mounted within an outer tube, said fluid chamber comprising another tube mounted within the outer tube, and cap members mounted on the outer ends of the outer tube for forming the head ends of said cylinder, a disc being clamped in between the inner ends of said inner tubes, resilient means acting against said disc and directly and indirectly against said piston for floating the piston, said resilient means for urging the stem comprising a member fixedly mounted on the stem, and an expansion spring acting between said disc and said member.

8. In an alternating or varying pressure or vacuum actuated pump, an air pump, an air cylinder having an air inlet and an air outlet, one way valves controlling said inlet and outlet, a piston in said cylinder, means for oscillating said piston to pump air from the inlet to the outlet, a stem slidably supported longitudinally on said piston and having a head engaging in a hollow in the piston arranged so that the piston moves the stem in one direction only, resilient means urging the stem in the other direction, a fluid chamber having a fluid inlet and a fluid outlet, one way valves controlling said fluid inlet and fluid outlet, a diaphragm in said fluid chamber, and said stem being connected with said diaphragm so that when the piston moves the stem, fluid is drawn into the fluid chamber and then the resilient means exerts a pressure on the fluid to force it out of the fluid outlet, said air cylinder comprising a tube mounted within an outer tube, said fluid chamber comprising another tube mounted within the outer tube, and cap members mounted on the outer ends of the outer tube for forming the head ends of said cylinder, a disc being clamped in between the inner ends of said inner tubes, resilient means acting against said disc and directly and indirectly against said piston for floating the piston, an auxiliary disc supported by said inner and outer tubes, and resilient means acting between said auxiliary disc and a member mounted on said stem for resiliently urging said stem in a direction to cause said diaphragm to exert a pressure upon fluid in said fluid chamber.

9. In an alternating or varying pressure or vacuum actuated pump, an air pump, an air cylinder having an air inlet and an air outlet, one way valves controlling said inlet and outlet, a piston in said cylinder, means for oscillating said piston to pump air from the inlet to the outlet, a stem slidably supported longitudinally on said piston and having a head engaging in a hollow in the piston arranged so that the piston moves the stem in one direction only, resilient means urging the stem in the other direction, a fluid chamber having a fluid inlet and a fluid outlet, one way valves controlling said fluid inlet and fluid outlet, a diaphragm in said fluid chamber, and said stem being connected with said diaphragm so that when the piston moves the stem, fluid is drawn into the fluid chamber and then the resilient means exerts a pressure on the fluid to force it out of the fluid outlet, said air cylinder comprising a tube mounted within an outer tube, said fluid chamber comprising another tube mounted within the outer tube, and cap members mounted on the outer ends of the outer tube for forming the head ends of said cylinder, a disc being clamped in between the inner ends of said inner tubes, resilient means acting against said disc and directly and indirectly against said piston for floating the piston, said resilient means for urging the stem comprising a member fixedly mounted on the stem, and an expansion spring acting between said disc and said member, and an annular member mounted upon said disc and adapted to be adjusted relative thereto and abutting said spring to control its resiliency.

10. In an alternating or varying pressure or vacuum actuated pump, an air pump, an air cylinder having an air inlet and an air outlet, one way valves controlling said inlet and outlet, a piston in said cylinder, means for oscillating said piston to pump air from the inlet to the outlet, a stem slidably supported longitudinally on said piston and having a head engaging in a hollow in the piston arranged so that the piston moves the stem in one direction only, resilient means urging the stem in the other direction, a fluid chamber having a fluid inlet and a fluid outlet, one way valves controlling said fluid inlet

and fluid outlet, a diaphragm in said fluid chamber, and said stem being connected with said diaphragm so that when the piston moves the stem, fluid is drawn into the fluid chamber and then the resilient means exerts a pressure on the fluid to force it out of the fluid outlet, said air cylinder comprising a tube mounted within an outer tube, said fluid chamber comprising another tube mounted within the outer tube, and cap members mounted on the outer ends of the outer tube for forming the head ends of said cylinder, a disc being clamped in between the inner ends of said inner tubes, resilient means acting against said disc and directly and indirectly against said piston for floating the piston, an auxiliary disc supported by said inner and outer tubes, and resilient means acting between said auxiliary disc and a member mounted on said stem for resiliently urging said stem in a direction to cause said diaphragm to exert a pressure upon fluid in said fluid chamber.

11. In an alternating or varying pressure or vacuum actuated pump, an air pump, an air cylinder having an air inlet and an air outlet, one way valves controlling said inlet and outlet, a piston in said cylinder, means for oscillating said piston to pump air from the inlet to the outlet, a stem slidably supported longitudinally on said piston and having a head engaging in a hollow in the piston arranged so that the piston moves the stem in one direction only, resilient means urging the stem in the other direction, a fluid chamber having a fluid inlet and a fluid outlet, one way valves controlling said fluid inlet and fluid outlet, a diaphragm in said fluid chamber, and said stem being connected with said diaphragm so that when the piston moves the stem, fluid is drawn into the fluid chamber and then the resilient means exerts a pressure on the fluid to force it out of the fluid outlet, said air cylinder comprising a tube mounted within an outer tube, said fluid chamber comprising another tube mounted within the outer tube, and cap members mounted on the outer ends of the outer tube for forming the head ends of said cylinder, a disc being clamped in between the inner ends of said inner tubes, resilient means acting against said disc and directly and indirectly against said piston for floating the piston, an auxiliary disc supported by said inner and outer tubes, and resilient means acting between said auxiliary disc and a member mounted on said stem for resiliently urging said stem in a direction to cause said diaphragm to exert a pressure upon fluid in said fluid chamber, said member comprising a flanged disc, and said resilient means comprising a spring resting against said flanged disc.
